THEODORE ATEN, OF FLORAL PARK, NEW YORK.

CONCRETE CONSTRUCTION.

1,307,432.

Specification of Letters Patent. Patented June 24, 1919.

Application filed December 9, 1914. Serial No. 876,201.

To all whom it may concern:

Be it known that I, THEODORE ATEN, a citizen of the United States, residing in Floral Park, Long Island, New York, have 5 invented certain new and useful Improvements in Concrete Construction, of which the following is the specification.

My invention relates to the elimination in concrete construction of the use of a temporary mold, the mold and reinforcing being 10 combined into a single structural member which performs the functions of both. This is accomplished in such a manner that the concrete may still be "poured" as in the case 15 of the previous type of construction in which temporary molds were utilized. In my improved construction I use as the combined mold and reinforcement a reticulated structure, preferably in the form of a coarse wire 20 screen, the interstices of which are sufficiently large to permit the finer grade of concrete to pass through but obstructing the passage of the coarser concrete therethrough and thereby embed the mold, thus converting 25 it into a permanent reinforcement.

In the construction of the concrete structure of the present invention, a hole is first dug having a substantially vertical lateral wall, thereupon a reticulated structure is inserted into the hole to form with the lateral 30 wall of said hole an annular space, and then concrete is poured into the annular space thus formed, whereupon the finer concrete will pass through the interstices of 35 said wall, to prevent the passage of the coarser concrete therethrough and the finer concrete which is disposed on the inner face of the reticulated structure, then smoothed down if desired to form a finished inner face 40 for the wall being constructed. The reticulated member particularly adapts itself first to serve as a mold face in the construction of the concrete structure, then to permit its being embedded in the concrete to subsequently 45 serve as a permanent reinforcement for the structure when completed, and furthermore to coöperate with the concrete itself to retain the coarser concrete where most required for the stability of the structure and to permit the automatic distribution 50 of the finer concrete so that it can be utilized to the best advantage, namely, to be quickly formed into a finished inner face for the completed structure.

My invention also relates to a certain improved type of construction having the above

characteristics and particularly adapted for sewage disposal systems or other installations in which it is desirable to form a concrete tank below the surface of the ground. 60 This construction, in which the mold and reinforcing means are the same, has the very great advantage of being adapted to be shipped "knocked down," that is, with the parts disassembled. It is light and may be 65 packed into small compass, particularly adapting it for use by persons who are situated in country districts at remote distances from manufacturing centers.

In the accompanying drawings, which 70 form a part of this specification, Figure 1 is a vertical sectional view of a sewage disposal system illustrating my improved method of construction. Fig. 2 is a fragmentary vertical sectional view on an enlarged scale showing a portion of the upper 75 part of the wire mesh or screen, the manhole collar and the crownpiece which connects them. Fig. 3 is a plan view of the tank at the left of Fig. 1, and Fig. 4 is a fragmentary detail view, showing the manner of connecting together the overlapping edges of the mesh or screen.

Referring to the drawings in detail, the numeral 1 designates a combined mold and reinforcement for a tank. This combined mold and reinforcement is composed of a sheet of wire screen which may, for example, be constructed of No. 19 Brown & Sharpe gage wire with from 2 to $2\frac{1}{2}$ meshes 80 to the inch. The screen is curved to form an annulus or hollow cylinder and is placed in a hole 2 excavated in the earth. The wire screen may be provided at intervals with any suitable vertical reinforcing members 3. The vertical overlapping edges of the screen may be joined in the manner illustrated in Fig. 4, in which stove bolts 4 are passed through the meshes of the overlapping edges at suitable intervals and thereby 100 fasten the edges together. Into the annular cavity 5 between the screen and the earth, may be poured the concrete 6. This concrete will be retained at one side by the earthen wall and at the other side by a wire 105 screen. If a suitable mixture of concrete is used, such as that formed by one part of cement, $2\frac{1}{2}$ parts of sand and 5 parts of stone, a certain portion of the concrete will 110 pass through the meshes of the wire screen as indicated at 7 in Fig. 1. This seepage of the concrete will be sufficient to form a

- coating on the inner side of the wire fabric, thus effectually embedding the fabric so that it will act as a reinforcement for the concrete as well as initially forming a mold.
- 5 When the height of the tank is considerable, it may be advisable to use temporary reinforcing means for the screen, such as narrow hoops 8, the ends of which overlap, as shown in Figs. 1 and 2, and which may be secured together by means of the bolts 9. These hoops simply stiffen the wire fabric against inward bending and may be removed after the concrete has set. Since when in place they cover only a small fraction of the internal area of the tank, the fact that they prevent seepage of the concrete mixture through the mesh of the fabric at the points where they are temporarily situated does not weaken the reinforcing action of the wire mesh upon the concrete to any appreciable extent.
- 10 After the wire mesh has been erected in place, as shown in Fig. 1, a crownpiece for the structure is mounted upon it. This crownpiece preferably consists of four sheet metal segments 10 which overlap at their edges and are secured together by the bolts 11, thus forming a frusto-conical member. Around the bottom periphery of this member are formed a plurality of inturned lugs 12 formed by slitting the metal at 13 and 14 and then bending the lugs 12 inward. When the crownpiece is in position, these lugs are substantially vertical and abut against the inner surface of the wire fabric, as clearly shown in Figs. 1 and 2. Stove bolts 15 may be passed through suitable holes in these lugs and through the wire mesh, thus clamping the crownpiece firmly upon the wire fabric.
- 15 At the upper edge the crownpiece is secured to a manhole collar 16, which is provided with an outwardly and downwardly sloping flange 17 in line with the crownpiece and to which it is attached by means of the bolts 18. The upper periphery of the manhole collar is provided with a horizontally extending flange 19, adjacent to which is an inwardly extending flange 20 forming a seat for the cover 21.
- 20 In Fig. 1 I have shown the molds in place for the construction of a sewage disposal plant comprising a liquefying tank at the left and a siphon chamber at the right, together with the necessary inlet siphon and discharge pipes, but it will not be necessary to describe the structure in detail, since my invention is directed to the concrete construction. Fig. 1 shows a small amount of concrete 6 to have been poured into the
- 25 space 5 between the mesh and the earth wall. In completing the structure the concrete is poured in until this space between the wire mesh and the ground is completely filled and the concrete is then carried up along the dotted lines 22 in Fig. 1, forming a conical

construction or crown, this part of the concrete being retained in position while hardening by the sheet-metal crownpiece.

It will be seen that the construction above described provides an efficient knockdown 70 combined mold and reinforcement for concrete tanks and the like. Since the use of these tanks is principally in country districts, remote from large cities, it is exceedingly desirable that the expense attendant upon construction of temporary forms be done away with. My invention providing, as it does, a combined mold and reinforcement entirely constructed of sheet metal or wire screen, is light, simple and may be 75 packed for shipment in small compass, and requires no expert erector to put it in place. Furthermore, its use is superior to concrete tanks formed with wooden, or other molds, in which there is no reinforcing provided, 80 since the wire mesh adds a considerable degree of strength to the structure when it becomes embedded in the concrete as the latter sets or hardens.

While I have illustrated and described 90 only one specific embodiment of my invention, I realize that it is susceptible of broad application and I do not desire to be limited to the precise structure shown and described.

Having thus described my invention, I 95 claim:

1. The method of forming subterranean concrete tanks and the like, consisting of digging a hole in the ground, inserting a metal screen in said hole, said screen extending adjacent to the side walls of the hole so as to leave a narrow space between said screen and said side walls, filling concrete into said space from the top, some of said concrete seeping through the interstices of 100 said screen in the direction of the center of the tank, so as to interlock with said screen whereby said screen serves as a mold during the construction of the tank, but becomes 105 embedded in the concrete so as to form a permanent reinforcement therefor.

2. In concrete construction, a mold for tanks and the like comprising a substantially vertical combined mold-wall and reinforcement formed of an annular reticulated member, and a crownpiece therefor comprising a frusto-conical sheet-metal member having integral inturned lugs about its lower periphery for engagement with the upper edge of said vertical wall, said lugs being substantially vertical when the parts are assembled to engage and stiffen the upper edge of said wall.

3. In concrete construction, a mold for tanks and the like, comprising a substantially vertical combined mold-wall and reinforcement formed of an annular reticulated member, and a sheet-metal crownpiece therefor having integral inturned lugs about its lower periphery for engagement of the 125

upper edge of said reticulated member, said lugs lying inside of said edge.

4. A knockdown mold for subterranean concrete tanks and the like, comprising a flat reticulated metal structure adapted to be formed into an annular member constituting a combined mold-wall and reinforcement and a plurality of sheet-metal segments adapted to be formed into a frusto-conical crownpiece for said annular member and to hold said reinforcement in position and a manhole collar adapted to be attached to said segments to hold the upper ends of said segments in position.

15 5. A knockdown mold for subterranean concrete tanks and the like, comprising a flat reticulated metal structure adapted to be formed into an annular member constituting a combined mold-wall and reinforcement, and a plurality of sheet-metal segments adapted to be formed into a frusto-conical crownpiece for said member, said segments being provided with integral in-turned lugs for engagement with the top edge of said annular member whereby the latter is held in fixed supported position.

6. A knockdown mold and reinforcement for subterranean tanks and the like, comprising a flat reticulated metal structure, adapted to be formed into an annular member constituting a combined mold-wall and reinforcement, a hoop adapted to be sprung inside of said annular member to hold the same in shape, a plurality of sheet-metal segments, means for connecting the said segments to form a frusto-conical crownpiece, means for connecting said segments to the upper edge of said annular member, whereby said segments when formed into said crownpiece will hold said annular member in shape, a manhole collar, and means for attaching said manhole collar to the upper edges of said segments.

7. A subterranean reinforced concrete tank, comprising an annular reticulated metal mold and reinforcing member, a crownpiece for said member, comprising a plurality of sheet-metal segments attached to each other on their side edges and bent into frusto-conical shape, said segments having portions bent down adjacent to their outside edges to form integral in-turned lugs extending inside of the upper edge of said reticulated member and secured thereto, a manhole collar secured to the upper edges of said segments, and a filling of concrete inclosing said reticulated member and interlocking therewith and covering said crownpiece.

60 8. The method of forming subterranean tanks and the like which consists in digging a hole in the ground, inserting a metal screen in said hole adjacent to the side walls thereof but spaced therefrom so as to leave

65 a narrow space between said screen and said

walls, connecting metal segments to form a frusto-conical top, connecting said top at its periphery to the upper edge of said screen, whereby said top and screen mutually act to retain each other in place, and 70 filling concrete from above into the space between said screen and the earth wall, and permitting some of said concrete to penetrate the openings in said screen from the outside toward the center of the tank, so 75 as to embed the screen therein, whereby a reinforced wall is produced without the use of centering.

9. A knock-down mold and reinforcement for subterranean tanks and the like, comprising an annular reticulated metal structure constituting the combined mold wall and reinforcement, a top member comprising a plurality of flexible metal segments and a man hole ring and detachable means 80 for connecting said segments to said reticulated metal structure and to said man hole ring, said reticulated metal wall structure and said top member mutually co-acting to support and retain each other in shape. 90

10. A self-sustaining mold and reinforcement for subterranean tanks and the like, comprising an annular reticulated metal structure constituting a combined mold wall and reinforcement, and a top member comprising a plurality of sheet metal segments detachably connected to each other and to said reticulated structure and a man hole ring detachably connected to the upper edges 95 of said segments.

11. A reinforced concrete tank or the like comprising a bottom, side walls and top, said bottom being formed of concrete, said side walls being formed of an annular reticulated metal reinforcement covered with concrete on the outside and wholly embedded by concrete permeating through the openings therein, and a top comprising a plurality of sheet metal segments connected together into frusto-conical form and attached at their 100 outer edges to said annular reticulated member and having a man hole ring connected to their inner edges and a covering of concrete over said sheet metal segments and around said man hole ring. 110

12. A knockdown mold for subterranean concrete tanks and the like, comprising a reticulated flexible metal structure adapted to be formed into annular shape to constitute a combined mold wall and reinforcement, a plurality of flexible metal segments adapted to be formed into a frusto-conical crown piece for said annular member, a rigid man hole ring adapted to be connected to said metal segments and means for connecting 120 said segments together and to said mold wall and man hole ring to produce a self-sustaining structure adapted to be covered with concrete to form a tank.

13. In a subterranean concrete tank and 130

the like formed in a hole in the ground having a lateral face, the combination with an annular pervious metal wall disposed a short distance from said lateral hole face and with 5 said lateral hole face forming an annular space, and a concrete filler disposed in said annular space projecting through said metal wall so as to interlock therewith whereby said metal wall constitutes a permanent re- 10 inforcement for the tank.

14. The method of forming a subterranean tank which consists in digging a hole in the ground, inserting a pervious metal wall in said hole and forming with the side walls of 15 said hole an annular chamber, filling concrete from above into said annular chamber, retaining the coarser grade of concrete behind said metal wall and permitting the finer grade to seep therethrough, and 20 smoothing down the finer grade of concrete thus seeping through to form the finished inner face of the said tank.

15. In a subterranean concrete tank and the like formed in a hole in the ground hav-

ing a substantially vertical lateral face, the 25 combination with a substantially vertical annular pervious metal wall disposed a short distance from said lateral hole face and with said lateral hole face forming an annular space, and a concrete filler disposed 30 in said annular space and projecting through said metal wall so as to interlock therewith whereby said metal wall constitutes a permanent reinforcement for the tank, the interstices of said metal wall being of a size 35 relative to the grade of concrete being used to permit the finer concrete to seep therethrough and spread over the inner face of said metal wall, but prevent the coarser concrete from passing therethrough whereby 40 the finer concrete may with facility be smoothed down to form a finished inner face for the tank.

THEODORE ATEN.
